J. LEONARD

BRASSIÈRE

Filed May 12, 1922

Inventor,

Joseph Leonard,

By *Horsay & Cole*
Attorneys.

UNITED STATES PATENT OFFICE.

JOSEPH LEONARD, OF ALLENTOWN, PENNSYLVANIA, ASSIGNOR TO FIFTH AVENUE CORSET COMPANY, INC., OF ALLENTOWN, PENNSYLVANIA, A CORPORATION OF NEW YORK.

BRASSIÈRE.

Application filed May 12, 1922. Serial No. 560,296.

To all whom it may concern:

Be it known that I, JOSEPH LEONARD, a citizen of the United States of America, and a resident of the city of Allentown, 5 county of Lehigh, and State of Pennsylvania, have invented certain new and useful Improvements in Brassières, of which the following is a specification.

The object of this invention is to provide a single garment which will combine the function of a corset in supporting and reducing the abdomen with the function of a brassière in confining the bust with a fabric of soft and more yielding construction and 15 affording suitable points of attachment for the hose supporters. A further object is to provide a construction which will afford adjustment of the two parts relative to each other.

20 In the accompanying sheet of drawing which forms a part of this specification the figure is a view in elevation of a brassière and reducing band made and combined in accordance with this invention, parts being 25 broken away.

The brassière is a soft fabric bodice 1 which completely encircles the body at the waist and for a sufficient distance above for suitably confining the bust. It also extends 30 below the waist and has extensions 2, 2 for hose supporter tapes. It is fastened by a line of hooks and eyes 3, 3 at the back. Toward the sides of the front of the brassière and below the waist are vertical lacing 35 strips 4, 4 for connection by lacing with lacing strips 5, 5 at the sides of a reducing band 6. The attachments of the lacing strips to the band may be through elastic sections 7, 7. The lacing strips attached to 40 the brassière are longer than the lacing strips attached to the reducing band so that the reducing band may be connected at higher or lower points as is found desirable. The reducing band has bones 8, 8 to give it the necessary stiffness and when worn curves 45 under the abdomen to the groins. The brassière overlies the reducing band and is not connected directly thereto except through the lacing and through a depending tab 9 which is united to the reducing band by a horizontal line of stitching 10. Consequently any draft on the front extensions to the hose supporter tapes will not 50 tend to shift the reducing band. Elastic sections 11, 11 are provided in the portion of

the brassière which overlies the reducing band and they yield to allow the band to be drawn as tight as may be necessary.

The foregoing detailed description has been given for clearness of understanding 60 and no undue limitation should be deduced therefrom but the appended claims should be construed as broadly as permissible in view of the prior art.

What I claim is:—

1. In combination, a brassière comprising a soft fabric bodice which completely encircles the body, and a continuous stiffened reducing band which is located under the lower portion of the front of the brassière 70 and connected for vertical adjustment at its sides to the brassière, and flexible means connecting the reducing band at its middle to the brassière.

2. In combination, a brassière comprising a soft fabric bodice which completely encircles the body and is provided with elastic sections in the lower portion of the front, and a stiffened reducing band which is located under the lower portion of the front 80 of the brassière and adjustably connected at its sides to the brassière beneath the elastic sections, and flexibly and permanently connected at its middle to the brassière.

3. In combination, a brassière comprising a soft fabric bodice which completely encircles the body and is provided with elastic sections in the lower portion of the front, and a continuous stiffened reducing band which is located under the lower portion of the front of the brassière and permanently connected at its middle to the brassière, and adjustably connected at its sides to the brassière beneath the elastic sections.

4. In combination, a brassière comprising a soft fabric bodice which completely encircles the body, a reducing band which is located under the lower portion of the front of the brassière and permanently connected at its middle to the brassière, means adjustably connecting the ends of the reducing band to the brassière, and elastic sections in the lower portion of the front of the brassière overlying the said adjustable connecting means.

Signed at Allentown, Pennsylvania, this 8th day of May, 1922.

JOSEPH LEONARD.
